J. W. FRY

STABILIZING SPRING

Filed March 28, 1927

FIG 1

FIG 3

FIG 4

John W. Fry
INVENTOR.
BY *G. Chapman*
ATTORNEY.

UNITED STATES PATENT OFFICE.

JOHN W. FRY, OF STRUTHERS, OHIO.

STABILIZING SPRING.

Application filed March 28, 1927. Serial No. 179,157.

This invention relates to vehicle springs and more particularly to springs for automobiles.

The principal object of this invention is to provide a spring so constructed that the weight or body carried by this spring will tend to be carried under momentum without subjecting the body or weight to any sudden, upward, downward or tilting motion.

10 A further object of this invention is to provide an upper and lower spring member, so arranged that the lower spring member constantly acts as a check against undesired movement of the body of the vehicle such as 15 upward or swaying movements which are common to vehicle bodies when suspended by springs of ordinary use when the vehicle is traveling over uneven road surfaces.

Another object of the invention is to provide upturned ends of a spring which are drawn down and caused to be at constant tension over an arc-shaped surface of two lever members functioning with an upper and lower spring and at suspension points 25 from the vehicle.

A still further object is to provide a spring device so constructed that the weight or body carried by said springs tends to be carried forward in a desired even way and not 30 materially affected by a light or heavy load.

With the foregoing and other objects in view which will appear as the description proceeds, the invention resides in the combination and arrangement of parts and in 35 the details of construction hereinafter described and claimed, it being understood that changes in the precise embodiment of the invention herein disclosed, can be made within the scope of what is claimed, without departing from the spirit of the invention.

The invention is illustrated in the accompanying drawing wherein:—

Figure 1 is a side elevation of the device.

Figure 2 is a sectional view taken on line

45 2—2 of Figure 1.

Figure 3 is a detail view showing a member of Figure 1.

Figure 4 is a detail view of Figure 1, showing an end of a spring with an upturned end not under tension.

By referring to Fig. 1 it will be seen that I have provided an ordinary vehicle axle 1 supported by wheels 2. The axle 1 is provided with support members 3 located near 55 the outer end of said axle.

As the description of this device proceeds, it will be seen that the entire weight of the load to be carried together with the stabilizing spring device is carried by these support members 3. The body or load of the vehicle to be carried rests upon any ordinary frame member 4. Rigidly attached to this frame member 4 at a central point 5 by means of clamps 6 is an upper spring 7 comprised of a plurality of leaves.

By referring to Fig. 4 it will be seen that the outer ends 8 of the upper spring 7 is provided with an upper curve when not under tension. The outer ends 8 as shown in Fig. 1 are under tension and securely 70 clamped to levers 9 by means of clamps 10.

The outer ends 11 of the levers 9 are secured to the support members 3 by means of shackles 12. The upper or inner ends 13 of the levers 9 are secured to a pair of 75 shackles 14. This pair of shackles 14 have their ends secured to a common pivot 15. This pivot 15 in turn is secured to a lower spring 16 by means of a clamp 17 which holds the common pivot 15 at a central point 80 on the lower spring 16, which is located directly underneath the upper spring 7. The outer ends 18 of the lower spring 16 are secured to shackles 19. The upper ends 20 of the shackles 19 are secured to yoke shaped 85 members 21 in such a manner as to allow for the clearness of the levers 9 at points 22 so that levers 9 may be allowed a desirable range of movement when the vehicle wheels 2 are subjected to uneven surfaces of a roadway. The upper ends 23 of the yoke shaped 90 members 21 are rigidly secured at the outer ends of the frame member 4 by any desirable means.

By referring to Fig. 3 it will be seen that the levers 9 are bifurcated at ends 11 and 13. It will also be seen that I have provided an upper curved surface 24 upon which functions a lower side of the spring 7.

The purpose of this upper curved surface 100 24 of the levers 9 is to provide a means for automatically shortening or lengthening the range of the spring 7 and to utilize the upturned ends 8 of the spring 7 when under tension, as the wheels 2 of the vehicle or the weight carried upon the frame member 4 are subjected to such movements as to cause an upward or downward movement of the inner ends 13 of the levers 9.

It is obvious that the upper spring 7 may 110

be made of any desired strength and length in order that the same may function within a range limited within its suspension. It is also obvious that the lower spring 16 may be made in varying lengths and strength in order to meet varying conditions which it is desirable to meet in constructing a spring device for varying roads and various constructions of vehicles. It is believed that under ordinary conditions the lower spring 16 should be built so as to be more flexible than the upper spring 7 in order to allow for a longer range of upward and downward movement of the wheels 2, without subjecting the load resting upon the frame member 4 to upward thrusts and rebounds or swaying or tilting movements. One of the common objections to springs utilized for the purpose of carrying loads is that very little consideration has been given to the undesirable action of springs which are set in motion when a vehicle travels over uneven surfaces. These undesirable actions of springs cause rebounds of the load carried and subject the wheels to undesirable downward thrusts into depressions in a roadway.

In this invention these undesirable actions of springs have been considered with a view of reducing these objectionable features to the minimum.

In the construction shown and described, it is obvious that the lower spring 16 when placed in proper assembly in connection with the other elements of the device should be under constant tension in order that the upturned ends 8 of the upper spring 7 are drawn down and also under constant tension, thereby producing reserve energy in the outer ends 8 of the spring 7 to be used to minimize the tendency of the wheels to be dropped violently into depressions of the roadway. In regard to the lower spring 16, it is obvious that when this spring has been assembled, as above described, there is a con-

stant downward pull at each outer edge of the frame member 4, thereby acting as a snubber for checking rebounds that would otherwise result when a vehicle is traveling over uneven roads.

What I claim is:

1. In a device of the class described, in combination with an axle and support members attached thereto, two levers inserted between two springs, the outer ends of said levers pivotally connected to the supports attached to the axle, the upper spring rigidly secured at a central point to a frame member to which is attached a body, a lower spring and means for securing outer ends of said lower spring to outer ends of the frame member above mentioned, inner ends of said levers pivotally attached to said lower spring, a curved upper surface on each of said levers, upturned ends of said upper spring, means for keeping said outer ends of upper spring under constant tension, substantially as described for the purpose set forth.

2. In a device of the class described, an axle and support members attached thereto, two levers inserted between two springs, the outer ends of said levers pivotally connected to the supports attached to the axle, the upper spring rigidly secured at a central point to a frame member to which is attached a body load, a lower spring and means for securing outer ends of said lower spring to outer ends of the frame member above mentioned, inner ends of said levers pivotally attached to said lower spring, a curved upper surface on each of said levers, upturned ends of said upper spring, means for keeping upper and lower springs under constant tension, means for keeping outer ends of upper spring pulled down against curved upper surface of each of said levers and under tension.

In testimony whereof I affix my signature.

JOHN W. FRY.
